UNITED STATES PATENT OFFICE.

CHARLES F. SPLITDORF, OF NEW YORK, N. Y.

VIBRATOR-REGULATOR.

SPECIFICATION forming part of Letters Patent No. 785,056, dated March 14, 1905.

Application filed January 23, 1904. Renewed January 24, 1905. Serial No. 242,563.

To all whom it may concern:

Be it known that I, CHARLES F. SPLITDORF, a citizen of the United States of America, and a resident of the borough of Manhattan, in 5 the city, county, and State of New York, have invented certain new and useful Improvements in Vibrator-Regulators, of which the following is a specification.

This invention relates to a novel means of 10 regulating and adjusting the tension of vibrators or interrupters for induction-coils; and my invention is herein shown and described as applied in conjunction with the strip or ribbon-spring vibrator forming the subject of a 15 concurrent application herewith.

In brief, my invention consists of a regulating-screw passed into a threaded support and having a diminished end that engages 20 with a spring whose opposite end is rigidly held, said screw having a knurled head by which it may be turned and also having a series of corrugations arranged around its periphery, together with a ball or other rolling body tensionally held part way within one of 25 said corrugations to determine and set or lock the position of the regulating-screw, but said ball or rolling body being capable of rolling into an adjacent corrugation upon the application of sufficient turning pressure to said 30 screw to expand the tensional support for said ball or rolling body and enable the latter to pass over the dividing-wall.

In the drawings accompanying this application, Figure 1. Fig. 2 is a central section 35 taken through the regulating and adjusting mechanism. Fig. 3 is a view taken on the line X X of Fig. 2, and Fig. 4 is a plan view of one of the spring-leaves.

The letter A indicates a coil-casing, and B 40 the core of the coil, forming an electromagnet. Mounted upon the casing A is the usual bridge C, carrying the adjusting-screw D, provided with the contact-point d. An armature, as E, is secured at one end to a mount, 45 as F, and is supported in the field of the electromagnet, as usual. The movable contact, as g, is borne by a ribbon or strip of thin sheet metal, as G, which latter is located between the adjusting-screw and armature, being 50 secured at one end to a rigid mount, as g', its

opposite end being held and provided with means for increasing or diminishing the tension of said spring. The mount F is recessed at one side to receive the armature E, which is secured in said recess, and said mount is 55 recessed at its opposite side for the reception of spring G, a convex bearing-surface, as e, being formed in said recess for said spring. A plate, as H, is secured upon mount F to serve as a guide for spring G, and said plate 60 has a rearward extension h, provided with a threaded aperture in which is placed a screw I, whose diminished i enters a hole g' in the extremity of spring G. Thus the spring G is held between mount g' and screw I, and 65 the tension of said spring may be regulated by turning said screw I. Turning the screw I in one direction has the effect of depressing the end of spring G that projects beyond the mount F, thereby drawing said spring taut 70 and giving it a requisite degree of tension, while turning the screw in the other direction serves to relax such tension.

A stud J, having a head j, is mounted upon the armature E and is adapted to protrude 75 through a slot g' in spring G, being entered through an enlargement of said slot and operatively adjusted, so that said spring is in the path of said stud-head j, to be hammered thereby in the movement of the armature 80 when attracted by the electromagnet.

The screw I is provided with an enlarged portion bearing a series of longitudinal depressions or corrugations K, arranged about its periphery, and a ball k, of steel or other 85 hard substance, is tensionally held in one of said depressions or corrugations. The tensional support referred to consists of two spring-leaves k' k'', placed together and secured at one side to the edge of extension h, 90 while at an opposite point said spring-leaves are tensionally separated by the ball k, which is held within opposite circular orifices formed in both said leaves. Said ball k, projecting through one or both the orifices in said leaves 95 k' k'', is held tensionally by said spring-leaves within one of the depressions or corrugations K, thus forming a set or lock for screw I; but by the exertion of sufficient force in turning the screw I, the operator grasping its 100

- knurled head I' in so doing, the spring-leaves $k' k^2$ are caused to expand and enable the ball k to roll from one depression or corrugation into another, passing with minimum frictional resistance over the intervening rib or wall because turnably held within the circular orifices provided in the leaves $k' k^2$. Thus, while said ball k forms a positive lock for the screw I, which lock cannot loosen through vibration or otherwise accidentally, a very durable locking device is provided through the absence of frictional wear in its manipulation, and it is furthermore operated with the greatest ease.
- 15 As is obvious, a roller or other turnable body might be substituted for the ball k , in such case corresponding bearings of course being provided in the leaves $k' k^2$.
- I claim—
- 20 1. A tension-regulator for vibrators or interrupters comprising a screw member and a

threaded support therefor, said screw member bearing a series of peripheral depressions; together with a lock for said screw member comprising a circular body tensionally held ²⁵ in one of said depressions and adapted to roll into an adjacent depression upon the application of turning force to said screw.

2. A turnable body having an annular series of depressions together with means for locking said body in a set position, said means comprising a circular body held between two spring-leaves and protruding through an orifice in one of said leaves into one of said depressions.

Signed at New York this 19th day of January, 1904.

CHARLES F. SPLITDORF.
